UNITED STATES PATENT OFFICE.

KEAMON KUROSE, OF SEATTLE, WASHINGTON.

DESIGN FOR A TIRE-TREAD.

59,120.

Specification for Design. Patented Sept. 20, 1921.

Application filed November 24, 1920. Serial No. 426,296. Term of patent 7 years.

To all whom it may concern:

Be it known that I, KEAMON KUROSE, a subject of the Emperor of Japan, residing at Seattle, in the county of King and State of Washington, have invented a new, original, and ornamental Design for a Tire-Tread, of which the following is a specification, reference being had to the accompanying drawings, forming a part thereof.

In the drawings, Figure 1 is a fragmen-

tary plan view of a tire having a tread constructed in accordance with my new design; Fig. 2 is a fragmentary view in cross section on broken line 2, 2 of Fig. 1, and Fig. 3 is a view in cross section on broken line 3, 3 of Fig. 1.

I claim—

The ornamental design for a tire tread, as shown.

KEAMON KUROSE.
